CLAIM

The ornamental design for a pistol safe, as shown and described.

DESCRIPTION

FIG. 1 is a perspective view of a pistol safe showing my new design;

FIG. 2 is another perspective view of FIG. 1, shown in an open position;

FIG. 3 is a front view of FIG. 1;

FIG. 4 is a back view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1.

1 Claim, 8 Drawing Sheets(56)
